UNITED STATES PATENT OFFICE

150,241

DESIGN FOR A ZONE CHECK TICKET HOLDER

Andrew Main, Willoughby, Ohio

Application December 12, 1946, Serial No. 135,417

Term of patent 14 years

(Cl. D74—1)

To all whom it may concern:

Be it known that I, Andrew Main, a citizen of the United States and resident of Willoughby, Lake County, Ohio, have invented a new, original, and ornamental Design for a Zone Check Ticket Holder, of which the following is a specification, reference being had to the accompanying drawing, forming a part thereof.

In the drawing,

Fig. 1 is a perspective view of a zone check ticket holder showing my new design.

Fig. 2 is a rear elevational view of the same.

I claim:

The ornamental design for a zone check ticket holder, as shown.

ANDREW MAIN.
